UNITED STATES PATENT OFFICE.

JOHN E. CHAMBERS, OF SHELBYVILLE, AND JAMES M. MARTIN, OF INDIANAPOLIS, INDIANA, ASSIGNORS TO CHAMBERS MANUFACTURING COMPANY, OF SHELBYVILLE, INDIANA, A CORPORATION OF INDIANA.

GAS-BURNER.

1,200,078.

Specification of Letters Patent.

Patented Oct. 3, 1916.

Application filed February 9, 1915. Serial No. 7,088.

To all whom it may concern:

Be it known that we, JOHN E. CHAMBERS and JAMES M. MARTIN, citizens of the United States, residing, respectively, at 5 Shelbyville, in the county of Shelby, State of Indiana, and Indianapolis, in the county of Marion, State of Indiana, have invented certain new and useful Improvements in Gas-Burners, of which the following is a 10 specification, reference being had therein to the accompanying drawing.

This invention relates to gas burners for stoves, and the like, and has to deal, more particularly, with means for regulating the 15 mixture delivered to the burner. In devices of this character, many attempts have been made to vary the quantity of air supplied for the mixing chamber, and it is one of the objects of the present invention to 20 provide novel and inexpensive means for this purpose, which said means, though simple in construction, and neat in design, is highly efficient in use.

In carrying out the invention, we prefer- 25 ably take advantage of an extension of the burner to constitute the mixing chamber, and apply directly to said extension a novel type of air supply means, readily adjustable at will, and preferably having means 30 to retain the same in adjusted positions.

A further object of the invention is to provide, in combination, means for regulating the air supply, and means for regulating the fuel supply, the said means being operatively associated one with the other in 35 a novel and improved manner, while, at the same time independently adjustable at will, without interference one with the other.

Novel details in the construction and ar- 40 rangement of the several parts will be ap- preciated from the description to follow, which, for a clear understanding of the invention, is to be considered in connection with the accompanying drawings forming a 45 part hereof, and wherein is disclosed, for the purpose of illustration, a convenient and satisfactory embodiment of the invention.

In the drawings: Figure 1 is a side eleva- 50 tion of a burner with our improvements ap- plied; Fig. 2 is a plan view of the same, and Figs. 3, 4, 5 and 6 are detail views of the air regulating means.

With more particular reference to the drawings, wherein like reference numerals

refer to corresponding parts throughout the 55 several views, a burner is provided, the same being preferably of integral construction and having a hollow tubular body portion 1, with radially extending hollow arms 2, the body portion and said arms being pro- 60 vided with closely associated outlet openings 3, in the top thereof.

4 is a mixing chamber, the same prefer- ably being an integral tubular extension of 65 one of the arms 2, which said tubular ex- tension is threaded, at 4^a, and has a terminal 4^b, of reduced diameter.

5 is a fuel supply pipe, having therein a 70 rotatable cut off valve 6 of any desired con- struction and adapted to be operated through the medium of a handle 7. The supply pipe 5 is adapted to be rigidly sup- 75 ported in any desired manner, and has a threaded portion 8 adjacent the end thereof. Projecting from the threaded end of the fuel 75 supply pipe 5, is a suitable valve needle 9, said needle being supported from the sup- 80 ply pipe 5, so as to leave an open terminal for said pipe at the sides of said needle.

10 is a cap interiorly threaded, at 11, so 80 as to engage the threads 8 of the fuel sup- 85 ply pipe, the said cap 10 having an outlet opening 12, adapted to receive the pointed end of the valve 9 and coöperating with said valve to provide an adjustable outlet for the fuel, such as gas. Connected to the cap member 10 adjacent the rear end thereof is a suitable collar 13, having a roughened sur- 90 face whereby to constitute a hand engaging part to the end that the cap may be ad- justed at will to regulate the size of the out- 95 let passage.

As stated, the fuel supply pipe is prefer- ably rigidly supported in place with re- 95 spect to the mixing chamber 4, and the out- let end of the fuel supply, provided by the cap 10, is positioned within the inlet end of the mixing chamber, which said inlet end is provided by an unobstructed opening 4^c, at the terminal of said extension 4.

In order to accurately regulate the amount of air supplied to the mixing chamber, we 105 preferably provide a sleeve 14, having sepa- rated webs 15, adapted to connect with said sleeve a cap shaped part 16. The cap-shaped part 16 has a substantially central opening 17, the wall surrounding said opening being sleeved upon the adjustable cap 10, and the

annular portion of said cap member 16 is preferably roughened on its exterior surface to constitute hand engaging means.

The interior surface of the sleeve 14 and webs 15 are threaded to correspond with the threads 4^a, whereby to be adjustably supported in position on the wall of the mixing chamber. In order to maintain the adjustable sleeve for the air supply, in its various positions of adjustment, we preferably provide a slit 18, in said sleeve, and arrange at opposite sides of said slit an apertured lug 19.

20 is a bolt adapted to have threaded engagement with the walls surrounding the apertures of the lugs, the bolt 20 having a slotted terminal 21 to be engaged by a screw driver or the like. It will be seen that by turning the bolt the end of the sleeve may be 20 brought into tight engagement with the wall 4 of the mixing chamber, and that by loosening the bolt the sleeve 14 may be readily adjusted.

In operation, it will be observed that the operator may govern the supply of gas or other fuel by engaging the collar 13, and imparting radial movement thereto, which will relatively adjust the outlet end of the cap and the valve 9. Also, when desired, to regulate the air supply, this may be readily accomplished by loosening the bolt 20, when the sleeve 14 may be rotated, the quantity of air admitted into the chamber being determined by the amount of separation between the cap portion 16 and end 4^c of the mixing chamber. Should the sleeve 14 be adjusted inwardly to its limit, the annular portion of the cap 16 will overlie the smooth portion of the mixing chamber wall, and 40 the disk part of said cap will contact with the end of the mixing chamber so as to entirely shut off the air. By providing the terminal of the mixing chamber with a reduced diameter 4^b, it will be appreciated that the sleeve may be readily assembled upon the wall of the mixing chamber.

It will be appreciated from the description above that the air and fuel adjustments may be accomplished independently of the other and without interference one with the other by reason of the novel construction and coöperative relation of the parts adapted for this purpose.

It will further be appreciated that the air adjusting sleeve is of such construction that the air will be admitted from all sides of the burner tube at once—that is to say, the inlet end of the burner tube is open entirely therearound, with the exception of the relatively narrow webs of the adjusting sleeve, and these will not interfere noticeably with the inflow of the air at all sides of the burner tube.

Obviously, if desired, the air regulating sleeves 14 may be continuous and devoid of

the slit 18, and means other than that illustrated employed for locking the sleeve in adjusted positions, and in this connection, a locking nut 25 may be utilized, the same being sleeved upon the threaded burner extension, and after the sleeve 14 has been properly adjusted, said nut 25 may be brought into locking contact with the inner end of the sleeve 14 to thereby maintain the same against accidental displacement.

What we claim is:—

1. In a device of the character described, a burner having a tubular extension forming a mixing chamber, said extension being open at its outer end and having a threaded periphery, a sleeve having an interiorly threaded portion whereby to adjustably engage the threads of the wall of the mixing chamber, said sleeve having at its outer end a cap portion, said cap portion being connected to the sleeve by separated webs whereby to provide air inlets communicating with the open end of the tubular extension, which said air inlets are regulated by the adjustment of the sleeve, and said cap having an opening for fuel or the like.

2. In a device of the character described, a burner having a tubular extension forming a mixing chamber, said extension being open at its outer end and having a threaded periphery, a sleeve having an interiorly threaded portion whereby to adjustably engage the threads of the walls in the mixing chamber, said sleeve having at its outer end a cap portion overlying said open end of the tubular extension, and said cap portion being connected to the sleeve by separated webs whereby to form separated air openings, the size of which is regulated by adjustment of said sleeve, said cap also having an opening for fuel or the like, and a fuel supply pipe projecting through the cap opening, which said cap has a free sleeved engagement with said fuel supply pipe.

3. In a device of the character described, a burner, a tubular member connecting with the burner and having an opening at its opposite end for the admission of air and gas, means for regulating the supply of air admitted into said open end comprising a cap overlying said open end and having a threaded engagement with the periphery of the tubular member, said cap having peripheral openings communicating with the open end of the tubular member, the wall of the tubular member at its open end coöperating with the openings in the cap to regulate the intake of air by the screw threaded adjustment of said cap, and said cap having an end opening for the admission of gas.

4. In a device of the kind described, a burner, a tubular mixing chamber projecting therefrom open at its outer end, the wall of said chamber being threaded upon its periphery, and air supply means adapted to be

directly applied to the wall of said chamber comprising a sleeve having a threaded interior wall adapted to engage the threads of the wall of the mixing chamber, said sleeve having an end with a fuel supply opening, and peripheral openings adjacent to but spaced from said end whereby to constitute air inlets communicating with said open end of the tubular chamber, whereby upon longitudinal adjustment of the sleeve the size of the air intake into the tubular chamber is regulated, that portion of the sleeve adjacent its end being roughened to constitute hand engaging means whereby to adjust just the sleeve relative to the mixing chamber.

5. In a device of the character described, the combination of a burner having a tubular mixing chamber with an open end, the wall of which latter has a threaded periphery, a longitudinally adjustable air supply sleeve having an opening at its side communicating with the open end of the tubular chamber, and being threaded to the wall of the mixing chamber, whereby the air intake may be adjusted, said sleeve having an apertured end, a fuel supply pipe having an outlet end passing through the opening in the end of said sleeve, a needle valve at the outlet end of said fuel supply, and an adjustable cap coöperating with said valve to vary the fuel supply.

6. In a device of the character described, a burner, a tubular part having a threaded periphery, said tubular part having an open terminal, and air regulating means comprising a sleeve threaded to correspond with the threads of the tubular part, said sleeve having an end with a fuel inlet opening and one or more side openings adjacent said end, and means for maintaining the sleeve in adjusted positions.

7. In a device of the character described, a burner, a tubular part having a threaded periphery, said tubular part having an open terminal, and air regulating means comprising a sleeve threaded to correspond with the threads of the tubular part, said sleeve having an end with a fuel inlet opening and one or more side openings adjacent said end, 50 said sleeve having a slotted portion, and means to engage the sleeve to force the same in holding contact with the wall of said tubular member.

8. In a device of the class described, the combination of a tubular mixing chamber having an air inlet end opening, and air regulating means comprising a cap having an elongated tubular wall or sleeve fitted upon the mixing chamber, said sleeve having 60 openings adapted to register with the end opening of the mixing chamber, and said sleeve and wall of the mixing chamber having a threaded engagement with one another, whereby to lengthwise adjust the 65 sleeve and thereby regulate the quantity of air admitted to the end opening of the mixing chamber, said cap having a gas inlet opening, a gas conduit, a needle valve in the conduit, and an adjustable cap threaded to 70 said conduit and projecting through the cap of the mixing chamber and having an opening in registration with the terminal of the needle valve, substantially as and for the purpose described.

In testimony whereof, we have hereunto set our signatures in the presence of two witnesses.

JOHN E. CHAMBERS.
